UNITED STATES PATENT OFFICE.

FRANZ LÖSEL, OF BRUNN, CZECHOSLOVAKIA.

ELASTIC-FLUID TURBINE.

Application filed August 4, 1923. Serial No. 655,720.

To all whom it may concern:

Be it known that I, FRANZ LÖSEL, a citizen of the Republic of Czechoslovakia, and residing at Brunn, Czechoslovakia, have invented certain new and useful Improvements in and Relating to Elastic-Fluid Turbines, of which the following is a specification.

This invention relates to elastic-fluid turbines of the high-pressure type, and the 10 main objects of this invention are to improve the high-pressure turbine constructions, to reduce the weight, casing-dimensions, machining work and waste of material due thereto, and manufacturing costs of such 15 turbines, while very considerably increasing their reliability and safety.

Such castings must be made of considerable thickness to give the desired strength and consequently are very heavy and bulky 20 and proportionally expensive to manufacture. Such thickness and bulk do not, however, assure complete safety against cracking or explosion and in some respects even increase the danger for, although such casings 25 with thick walls or ribbed construction are fully capable of withstanding the fluid pressure, they are not so capable of withstanding the heat expansion stresses resulting from the existence of very high temperatures inside the casing and moderate temperatures at the outside thereof. Such heat expansion 30 stresses are very great and due to their inequality are very dangerous.

A further disadvantage connected with the 35 use of cast material consists in this that such material is porous, sucks up steam at the machined places and becomes spongy, which results, more particularly when the pressures and temperatures are high, in deleterious 40 conditions due to expansions and strains, which may have a bad effect on the working of the turbine and may lead to disaster.

For reducing the weight of turbines, it 45 has already been proposed to make the parts of the casing out of a solid roughly forged block by machining the internal and external surfaces, as is for instance usual in the case of the cylinders of motor cars, and aero-plane engines. This method, however, has 50 the great disadvantage that both the construction and the manufacture are connected with very great difficulties and that the manufacturing costs are very high, owing to the great number of places to be machined 55 and the great quantity of material wasted.

Hence this method of manufacture is out of the question at the present time for large high pressure steam or gas turbines.

It has also been proposed to construct the 60 turbine casing and internal parts entirely of sheet metal. A construction of this kind would have the advantage of low weight, but has not been taken up to any extent in practice, as it is difficult to make the internal 65 parts with sufficient accuracy and turbine casings of this kind easily become distorted and are not sufficiently rigid. The result of this would be, that those internal parts, more particularly the guide blade carriers, 70 which are connected to the casing, would be exposed to inadmissible changes of position. This well-known construction has the further disadvantage that the internal parts 75 are connected to the casing at many points, which interferes with the heat expansions.

The present invention is based on the 80 recognition of the fact that, for obtaining the requisite rigidity for the casing, even in the case of large turbines, the casing should consist not wholly, but only partly of cast material. As the disadvantages of cast material mentioned above apply more particularly to the high pressure part of the casing, according to the invention only that part 85 of the casing, which is subject to a higher driving fluid pressure, is made of rolled or pressed material, for instance, boiler plate, while that part of the casing, which is under a lower pressure, and the part supporting 90 the guides is made of cast material. In order to ensure that the parts supporting the guides may be securely mounted and that they may be free to expand when heated, these supporting parts are only connected 95 to the low pressure part of the casing, which is made of cast material or are cast in one piece with the same.

The accompanying drawing shows a constructional example of the invention,

Figure 1 being a longitudinal section 100 through a high pressure steam turbine and

Figure 2 a cross-section on the line A—B of Fig. 1.

The part *a* of the casing, which is under 105 high pressure, consists according to the invention of rolled or pressed material, for instance of boiler plate. The distributing chambers *c* for the driving fluid situated in front of the nozzles *b* are bounded by the part *a* of the casing and by the part *d*, which 110

also consists of boiler plate. The feed pipes *e* for the driving fluid are fixed into the wall *a* by rolling or welding together, but can also be fixed by being riveted, screwed on 5 or the like. The part *a* of the casing is connected by an annular flange *f*, which is also made of forged material, to the part *g* of the casing, which is under a lower pressure and is made of cast material. The parts *a*, 10 *d* and *f* can be riveted, bolted, welded together or the like.

The part *a* of the casing, which is under a high pressure, may be built up in certain cases, of a number of plates riveted, bolted, 15 welded or flanged together.

Within the parts *a* and *g* of the casing there is an inserted part *g'*, which carries the guide blades and the like and is connected by a spacing ring *h* to the part *g* 20 of the casing, being held exactly centrally. Preferably the inserted part *g'* is rigidly fixed to the part *g* of the casing or it may be in certain cases cast in one piece with it, which overcomes the difficulty of centring 25 and does away with the ring *h*. The rotor *i*, which is only partly shown in the drawing, is constructed in the usual manner.

In the case of high driving fluid pressures the usual horizontal division of the casing 30 provides certain difficulties, owing to the many and thick connecting bolts that are required for providing the necessary strength and obtaining a tight joint, for which reason it is preferable to divide the 35 casing, which is under high pressure, only at right angles to the axis. In the example shown the high pressure part *a* of the casing is therefore made of rolled material in one piece, while the part *g* of the casing, in 40 which the pressure is lower, is made in two parts and is held together by the horizontal flanges *j* (Fig. 1).

The undivided part *a* of the casing is taken apart by loosening the flange screws 45 *k*, *m* and by displacing this part of the casing in the axial direction. The parts lying within the part *a* of the casing, such as the inserted part *g'*, further the high pressure glands and bearings *n* and the like must 50 therefore be so designed as to allow of the part *a* of the casing being displaced axially. By the axial displacement of the part *a* of the casing the interior of the turbine is exposed, after which the rest of the turbine 55 may be taken to pieces in a simple manner.

According to the present invention the advantages of the cast turbine casings are retained and their disadvantages are to a great extent overcome, while the whole construction is lighter and the manufacture 60 simpler and cheaper, which is of special importance in the case of large turbines. The cast iron part of the casing gives the whole turbine casing the requisite rigidity, 65 while the wrought iron part only takes up

the stresses due to high pressure. By this means the stresses are distributed in a favourable manner over the two parts of the casing consisting of different materials and deleterious effects due to heat, more 70 particularly deformation and expansion due to heat, are avoided.

What I claim is:—

1. An elastic fluid turbine having a high pressure part and a low pressure part, a 75 casing for the high pressure part and a casing for the low pressure part, blading for guiding the elastic fluid and a supporting part for the said blading, the high pressure part of the casing being made of wrought 80 metal, such as boiler plate, and the low pressure part of the casing and the supporting part for the guide blading being made of cast metal, for the purpose set forth.

2. An elastic fluid turbine, as claimed in 85 claim 1, having the supporting part for the guide blading connected only to the part of the casing made of cast metal, as set forth.

3. An elastic fluid turbine, as claimed in 90 claim 1, having a single circular flanged connection between the part of the casing made of cast metal and the part of the casing made of wrought metal, as set forth.

4. An elastic-fluid turbine comprising, in 95 combination, a high pressure casing made of wrought metal, such as boiler-plate, a low-pressure casing made of cast metal, a rotor enclosing stator casing of cast metal forming an inwardly projecting part of said 100 low-pressure casing, and concentrically spaced within the high-pressure casing.

5. An elastic-fluid turbine comprising, in combination a high pressure casing made of wrought metal, such as boiler-plate, a 105 low pressure casing made of cast metal and connected with the rear end of the said high-pressure casing, a rotor enclosing stator casing also made of cast metal and forming an inwardly projecting part of the low-pressure casing which is concentrically spaced within the wrought metal casing to form a space for the high-pressure fluid around the rotor enclosing casing.

6. A casing for an elastic-fluid turbine 115 comprising an outer high-pressure part formed of wrought metal and having at its high-pressure front end intake chambers for the high-pressure fluid, nozzles fixed on said intake chambers, a low-pressure part made of cast metal at the rear end, and a rotor enclosing stator casing also made of cast metal inwardly projecting from said low-pressure part to the nozzles on the intake chambers and said low pressure casing 120 forming, with the other high-pressure casing, a space to be filled with the high pressure fluid as a means to oppose the inner pressure of the fluid in the inner casing.

7. In an elastic fluid turbine having a high 130

pressure part and a low pressure part, blading for guiding the elastic fluid, a support for said blading, a cast metal casing for the low pressure part having the blading support connected therewith, and a relatively thin casing for the high pressure part constructed of material of high tensile strength, such as boiler plate, to avoid the

great and irregular stresses which would arise in a thick cast casing for the high ¹⁰ pressure part.

In testimony whereof I have signed my name to this specification.

FRANZ LÖSEL.
